UNITED STATES PATENT OFFICE.

JOHN F. ALBRECHT, OF GLENCOE, MINNESOTA.

CONVERTIBLE DUMP-CART.

1,171,578.

Specification of Letters Patent. Patented Feb. 15, 1916.

Application filed July 15, 1914. Serial No. 851,048.

To all whom it may concern:

Be it known that I, JOHN F. ALBRECHT, a citizen of the United States, residing at Glencoe, in the county of McLeod and State 5 of Minnesota, have invented certain new and useful Improvements in Convertible Dump-Carts; and I do hereby declare the following to be a full, clear, and exact description of the invention, such as will enable others 10 skilled in the art to which it appertains to make and use the same.

My invention relates to improvements in convertible dump carts; and, to this end, it 15 consists of the novel devices, and combinations of devices, hereinafter described and defined in the claims.

In the accompanying drawings, which illustrate the invention, like characters indicate like parts throughout the several 20 views.

Referring to the drawings, Figure 1 is a side elevation of a train, made up of a plurality of the improved carts, some parts being broken away; Fig. 2 is a plan view of 25 the same, with some parts removed; Fig. 3 is a side elevation of one of the improved carts, on an enlarged scale, equipped with combined brakes and steering device, said cart usually being placed at the rear of the 30 train; some parts being broken away; Fig. 4 is a plan view of the cart shown in Fig. 3, with some parts removed; Fig. 5 is a transverse vertical section, taken on the line $x^5 x^5$ of Fig. 4; Fig. 6 is a view, partly in end 35 elevation and partly in transverse section, taken on the line $x^6 x^6$ of Fig. 3, on an enlarged scale; and Fig. 7 is a detail view, principally in longitudinal vertical section, taken on the line $x^7 x^7$ of Fig. 4, on an en- 40 larged scale.

As all of the carts are identical in construction, the description of one will suffice.

The numeral 1 indicates a pair of relatively large wheels, journaled on axially 45 aligned stub axles 2, secured, one to each end of a bolster 3. As shown, this bolster 3 is made up of a pair of channel bars placed back to back and laterally spaced apart, as best shown in Fig. 7, with the inner ends of 50 the stub axles 2 extended therebetween and

rigidly secured thereto. Mounted on the bolster 3 is a rectangular frame 4, constructed of channel bars rigidly secured together with their flanges turned outward. Extending through the longitudinal center 55 of the frame 4 is a T-bar 5, rigidly secured at its ends to the end members of the frame 4. The frame 4 and bar 5 rest on the bolster 3 at their longitudinal centers, so that the same are balanced on said bolster, and are 60 rigidly secured thereto, by rivets or otherwise. The web of the bar 5 is relatively narrow and the upper flanges of said bar extend in the same horizontal plane with the horizontal flanges of angle bars 6, secured 65 to and within the frame 4.

The body 7 of the cart, as shown, has straight vertical ends and hopper-like sides. This body 7 is preferably constructed from 70 sheet metal, has an open bottom and is of a size to fit within the frame 4 and rest, at its lower edge, on the horizontal flanges of the angle bars 6. Said body may either loosely rest within the frame 4 or may be rigidly secured thereto.

The bolster 3 and bar 5 divide the open bottom of the body 7 into four rectangular openings. These openings are normally closed by four trap doors 8, hinged at their 75 inner ends to horizontal hinge rods 9, ex- 80 tended transversely of the frame 4 directly over the bolster 3, and anchored at their ends to the side members of the frame 4. By this arrangement, the two trap doors 8 on the same side of the bolster 3 are mounted on 85 the same hinge rod 9 and move in the same direction to and from open positions. These trap doors work under the top flanges of the bar 5 and the horizontal flanges of the angle bars 6, and, when in closed positions, overlap 90 said flanges, thus completely closing the open bottom of the body 7.

The pair of drop doors 8 on each hinge rod 9 is raised and lowered simultaneously by a windlass shaft 10, and a pair of flexible 95 connections 11. The windlass shafts 10 extend transversely of the body 7 directly over the free end portions of the drop doors 8 and are journaled in the sides of said body. On one end of each windlass shaft 10 is an 100

operating hand crank 12 and ratchet wheel 13. Coöperating with each ratchet wheel 13 is a pawl 14, pivoted to the body 7. The flexible connections or cables 11 are arranged 5 to be wound on the windlass shafts 10 and their outer ends are secured one to each of the drop doors 8. Obviously, by rotating the windlass shafts 10, the drop doors 8 may be raised or lowered, at will, and, by 10 turning the pawls 14 into engagement with the ratchet wheels 13, said shafts may be held in different set positions to hold the drop doors 8 closed, or in different open positions. As a supplemental means for locking 15 each drop door 8 closed, is provided an intermediately pivoted dog 15. These dogs 15 are pivoted at 16 to the lower flange of the end members of the frame 4 and their inner ends work through slots 17 formed in 20 the webs of said end members, and are of a length sufficient to extend under the drop doors 8, and hold the same closed. The two dogs 15, at each end of the frame 4, are connected at their outer ends, for simultaneous 25 movements, by an operating rod 18, having at each end a hand piece.

It is important to note that the drop doors 8 are carried entirely by the frame 4 and, when the body 7 is removed from the cart, 30 afford a platform suitable for hauling large stones, cement in sacks, or any heavy material that would be difficult to lift over the high sides of the body 7. To remove the body 7 from the frame 4, it is only necessary 35 to detach the cables 11 from the drop doors 8. When the body 7 is removed from the frame, the dogs 15 afford the only means for holding the drop doors 8 closed.

The improved carts which go to make up 40 the train are connected in tandem by a plurality of draw bars 19. These draw bars are pivotally connected by king bolts 20 on the carts to form a continuous draw bar throughout the length of the train. There 45 is one of these king bolts on each cart, and the same is located at the longitudinal center of the bolster 3, extends between the channel bars forming said bolster, and is provided at its lower end with a nut and a washer. These king bolts 20 also pivotally 50 connect the carts to the pivotal connections between the draw bars. On each end of the cart is rigidly secured a transversely extended guide strap 21, between which, and the end members of the frame 4, the draw bars 19 work.

To impart like angular turning movements to the different carts of the train, adjacent ends of said carts are connected by 60 crossed flexible connections 22. The ends of these flexible connections 22 are secured to the diagonally opposite side members of the frames of adjacent carts. The flexible con-

nections or chains 22, at the front end of the foremost cart, are directly connected, as 65 shown, to the foremost draw bar 19, which acts as a tongue in steering the first or foremost cart. The following carts will be secured by the cross connections 22.

The train may be drawn by a tractor or 70 other suitable motive power, to which the pole of the front cart is attached. In some instances, it might be desirable to connect the cross chains at the front end of the foremost cart directly to the tractor in order to 75 receive its steering movement. When the train is turning a curve, the axles of the carts will be radial of the center of the curve traveled, and the draw bars 19 will form the chords of the arc of the curve traveled. 80 Brakes are arranged for application to the wheels of the rearmost cart of the train. These brakes comprise a rock shaft 23, journaled in the rearwardly projecting ends of the side bars of the frame 4, crank arms 24, 85 rigidly secured to the outwardly projecting ends of said shaft, and shoe-equipped brake heads 25, pivotally secured to the free ends of the arms 24. To the intermediate portion of the rock shaft 23 is rigidly secured a rear- 90 wardly projecting hand piece or lever 26. By pressing downward on this lever 26, the brakes may be applied to the wheels, or, if pulled laterally by an operator, the train may be steered in any desired direction, 95 when the same is backing up.

As shown, the rock shaft 23 is removably journaled in pairs of open seats 27, formed in the ends of the side channels of the rectangular frame 4. By thus removably 100 mounting the brakes, the same may be readily applied to the rear end of the rear cart of the train, whenever a cart is added or detached from the train. In reversing the direction of travel of the train it is only necessary 105 to turn the tractor around and attach the same to the other end of the train, and change the brakes from one end of the train to the other.

What I claim is:

1. A cart comprising a rectangular frame, having inwardly projecting flanges located below its upper face, a bolster secured to the transverse center of said frame, wheels journaled on said bolster, dump doors secured to 115 said frame, means for securing said dump doors closed, and a body having its lower edge portion telescoped within said frame and removably supported on the inwardly projecting flanges thereof.

2. A cart comprising a rectangular frame, having inwardly projecting flanges located below its upper face, a bolster secured to the transverse center of said frame, wheels journaled on said bolster, a tie bar at the longitudinal center of the frame, resting on said

bolster and having flanges, located in the plane of the flanges of said frame, dump doors secured to said frame, and located below the flanges of said tie bar and frame,
5 means for securing said dump doors closed against the flanges of said tie bar and frame, and a body having its lower edge portion telescoped within said frame and removably

supported on the inwardly projecting flanges of said frame.

In testimony whereof I affix my signature in presence of two witnesses.

JOHN F. ALBRECHT.
